UNITED STATES PATENT OFFICE.

FRANK EVERTS, OF ST. LOUIS, MISSOURI, ASSIGNOR TO THE ST. LOUIS WOODEN WARE WORKS, OF SAME PLACE.

WASHBOARD.

SPECIFICATION forming part of Letters Patent No. 673,866, dated May 14, 1901.

Application filed October 26, 1900. Serial No. 34,285. (No model.)

To all whom it may concern:

Be it known that I, FRANK EVERTS, a citizen of the United States, residing at the city of St. Louis, State of Missouri, have invented 5 a certain new and useful Improvement in Washboards, of which the following is a full, clear, and exact description, such as will enable others skilled in the art to which it appertains to make and use the same, reference 10 being had to the accompanying drawings, forming part of this specification, in which—

Figure 1 is a front elevational view of my improved washboard. Fig. 2 is a rear elevational view. Fig. 3 is a sectional view on 15 line 3 3, Fig. 1; and Fig. 4 is a detail perspective view of the head.

This invention relates to a new and useful improvement in washboards, the object being to construct a head of sheet metal which 20 is so bent as to give it considerable strength and at the same time form a soap-holder which will direct the water draining from the soap onto and over the face of the rubbing-surface, so that the drainings from the soap 25 may be utilized instead of wasted, as would be the case if they fell behind the rubbing-surface.

With this object in view the invention consists in the construction, arrangement, and 30 combination of the several parts, all as will hereinafter be described and afterward pointed out in the claims.

In the drawings, A indicates the side rails, which are preferably grooved, as usual, to 35 receive the rubbing-surface and the backing therefor. This rubbing-surface is indicated at B and may consist of corrugated sheet metal backed by a backing C, or said rubbing-surface may be of other material.

40 D indicates a cross-strip arranged at the upper end of the groove, against which the rubbing-surface and its backing snugly fit. The front face of this strip D is provided with a groove d, as shown in Fig. 3.

45 The upper ends of the side rails A are rounded and slightly overhang in front, as shown.

E indicates a sheet-metal headpiece, which is provided with lateral wings e, designed to be secured to the rounded portions of the 50 rail-heads, while the body portion of this metallic headpiece is curved forwardly between the rails and over the strip D, the lower end of the headpiece being provided with a flange e', which fits into the groove d. 55

F indicates a rod or bar fitted in sockets in the inner faces of the rails A and located above the forward lower end of the headpiece and serving as a soap-support, at the same time permitting the water dripping 60 from the soap to pass under the support and onto and over the rubbing-surface. It is obvious that this rod F may be made of wood instead of metal.

I am aware that minor changes in the arrangement, construction, and combination of the several parts of my device can be made and substituted for those herein shown and described without in the least departing from the nature and principle of my invention. 65

Having thus described my invention, what I claim, and desire to secure by Letters Patent, is—

1. In a washboard, the combination with side rails, a cross-piece and a rubbing-surface secured therebetween, of a metallic headpiece provided with a reduced body portion located between the said side rails below the front edges thereof, and also provided at its upper end with lateral wings extending over 80 and secured to the top ends of the rails, the upper end of said headpiece constituting the top connecting-piece for the rails, the body portion of said headpiece being curved forwardly between the rails and secured to said 85 cross-piece to direct water onto the rubbing-surface, substantially as described.

2. In a washboard, the combination with side rails, a cross-piece and a rubbing-surface secured therebetween, of a headpiece 90 having its upper end portion bent, to conform to the upper ends of the side rails and secured on top thereof and extending from front to rear of said side rails, the body por-

tion of said headpiece being reduced and bent forwardly between the side rails and having at its lower end a rearwardly-turned flange entering a groove in the front face of 5 said cross-piece, and a cross-bar F near the lower end of the headpiece and spaced therefrom, substantially as described.

In testimony whereof I hereunto affix my signature, in the presence of two witnesses, this 15th day of October, 1900.

FRANK EVERTS.

Witnesses:

F. R. CORNWALL,
GEORGE BAKEWELL.
